UNITED STATES PATENT OFFICE.

JAMES WHITCOMB AND GAROLD C. J. GRAY, OF HASTINGS, NEBRASKA; SAID WHITCOMB ASSIGNOR OF ONE-EIGHTH. TO CHANCIE ELMER COBLENTZ, OF HASTINGS, NEBRASKA.

AUTOMOBILE-ENGINE.

1,380,088.

Specification of Letters Patent. Patented May 31, 1921.

Application filed October 23, 1919. Serial No. 332,631.

To all whom it may concern:

Be it known that we, JAMES WHITCOMB and GAROLD C. J. GRAY, citizens of the United States, residing at Hastings, in the 5 county of Adams and State of Nebraska, have invented new and useful Improvements in Automobile-Engines, of which the following is a specification.

This invention relates to automobile engines of the internal combustion type, and has particular reference to general improvements in the construction of such engines whereby the cost of construction and maintenance is reduced and the working efficiency of the engine increased.

One object of the invention is to provide an engine construction in which the parts supporting or containing the working elements, such as the cylinders, pistons, crank 20 shaft, etc., are separable and permit of the easy and quick assemblage of such parts in erecting the engine as well as their ready and more convenient removal or disassembly when it is necessary to clean, repair, 25 regrind, reboore or replace worn, broken or imperfect parts or to completely overhaul or take down the engine.

Another object of the invention is to provide a construction whereby the working 30 parts are more completely incased and protected from dirt, dust or other foreign substances and injury, whereby more efficient lubrication of certain parts is obtained as well as higher power from the impulses of 35 the explosive charges, and whereby greater simplicity of manufacture is secured.

With these and other objects in view, the invention consists of the features of construction, combination and arrangement of 40 parts, hereinafter fully described and claimed, reference being had to the accompanying drawings, in which:—

Figure 1 is a view in elevation, with parts broken away, looking toward one side of 45 the engine.

Fig. 2 is a similar view, with parts broken away and in section, looking toward the opposite side of the engine.

Fig. 3 is a vertical transverse section on 50 line 3—3 of Fig. 4.

Fig. 4 is a top plan view of the engine.

In the practical embodiment of our invention as shown in the drawings, wherein we have illustrated a motor of the overhead- 55 valve type, we provide an engine body 1

comprising a crank casing 2 and a cylinder casing 3, the said body being provided at its base with supporting and bolting flanges 4 whereby it is adapted to be secured to the engine body or chassis of the vehicle. The 60 crank and cylinder casings are properly divided on vertical and horizontal lines to separate the same into relatively fixed or stationary and removable sections, to permit of the ready application and removal 65 and accessibility of the working parts of the engine. To this end the crank casing and cylinder casing are divided longitudinally along a vertical line, as indicated at 5, and are also divided horizontally on one side of 70 the vertical center thereof along the lines 6 and 7 to provide removable sections 8 and 9 at one side of the engine body, the opposite side walls of the crank casing, cylinder casing and the bottom portion of the crank casing below the division line 7 being preferably 75 integral in a unitary structure. Bolts or other suitable fastening members 10 and 11 are provided for respectively securing the removable sections of the crank casing 80 and cylinder casing to the fixed portions thereof, whereby the parts are normally held detachably assembled. It will be understood, of course, that in practice the joints between the fixed and removable sections 85 may be suitably gasketed or packed, when required, to prevent leakage.

The end walls of the sections of the crank casing 2 are provided with mating semi-circular recesses 12 having countersunk end 90 portions 13 to receive bearing sleeves 14 journaled within said bearing openings and having flanges 15 fitting within the countersinks 13 to hold said bearing sleeves from longitudinal displacement. The sleeves 14 95 form bearings for the ends of the crank shaft 16 extending longitudinally within the crank casing 2 and outwardly through the end walls thereof, one end of said shaft being provided with the usual fly wheel 17. 100 The shaft 16 is provided with the usual cranks 18 and wrist pins 19 for connection with the connecting rods 20 to which the pistons 21 are attached.

The pistons 21 are arranged to operate 105 within cylinders 22, which are removably fitted within the cylinder casing 3. The respective cylinders 22 are separate from and independent of each other, each consisting of a substantially spool-shaped body, 110

said body comprising a main cylindrical portion of uniform diameter and having annular end flanges or enlargements 23 of greater diameter than the cylindrical main portion. The said end portions 23 of the substantially spool-shaped cylinders fit within circular seats 24 formed at the top and bottom of the valve casing by semi-circular bosses 25 provided upon and projecting inwardly from the fixed and removable sections of the cylinder casing, which bosses are brought into mating and seat forming relation to receive and clamp the ends of the cylinders when the removable section 9 is applied and bolted in position.

With the exception of the inwardly projecting bosses 25 the inner faces of the fixed and removable portions of the cylinder casing 3 may be smooth-surfaced or cored out to form a water circulating chamber 26, with the terminal portions of which communicate the flow and return pipes 27 and 28 connecting the opposite ends and bottom and top portions of said chamber with the radiator. The expanded or enlarged end portions 23 of the cylinders snugly fit within the seats 24 to prevent leakage of water from the chamber 26, and if desired these seats may be suitably packed. The body portions of the cylinders are of less diameter than the distance between the fixed and removable sections of the cylinder casing, and also serve to so dispose the body portions of the cylinders as to space the same from each other, thus providing longitudinal water flow channels on opposite sides of the cylinder and between the same and the fixed and removable walls of the casing, and cross channels between the cylinders and connecting said longitudinal channels, whereby the water is adapted to completely surround and flow around the cylinders and thus rapidly absorb heat therefrom and keep the same cool. Each cylinder is thus individually cooled by water circulating around the same whereby liability of overheating of the cylinders is much more effectually prevented than is possible in engines of ordinary construction.

The cylinder casing and cylinders are closed at their upper ends by a cylinder head 29 comprising an oblong rectangular block, plate or casting resting upon the upper surface of the cylinder casing and detachably secured thereto by screws or other suitable fastenings 30. This cylinder head is formed with fuel inlet passages 31 and exhaust passages 32, respectively communicating with inlet and exhaust ports 33 and 34 communicating through the bottom of the cylinder head with the upper ends of the cylinders, an inlet and a cooperating exhaust port communicating with each cylinder and the cylinder head being provided with an opening between said ports to receive the spark

plug or other firing device 35. The passages 31 and 32 preferably extend transversely from the center of the cylinder head, where they intersect the ports 33 and 34 toward the removable side or section of the cylinder casing, where they are connected with intake and exhaust manifolds 36 and 37 of ordinary or suitable construction and which are fastened to the detachable section 9 so as to be readily removed from the section 9 or removable therewith when said section 9 is detached from the fixed portion of the engine casing.

The ports 33 and 34 are controlled by the vertically movable inlet and exhaust valves 38 and 39, the stems of which project upwardly through the cylinder head and are associated with coiled cushioning and lifting springs 40 whereby the valves are adapted to be closed. The sets of intake and exhaust valves are arranged to be depressed and opened at properly timed intervals by the action of the rocker arms 41 and 42 connected with the upper ends of the lifter rods 43. The lifter rods 43 are arranged within a compartment or chamber 44 formed on the outer side of the fixed section of the cylinder casing 3 and are fitted to slide vertically in guides 45 and through guide openings 46 in the cylinder head 29, which cylinder head closes the upper end of the casing 44, the lower ends of said lifter rods being provided with the shoes 47 for co-operation with the valve actuating cams 48 on the valve actuating cam shaft 49 extending longitudinally through the base of the chamber 44. The cams 48 are arranged to operate the lifter rods at properly timed periods in the usual manner in the rotation of the shaft 49 which carries a gear 50 meshing with a drive gear 51 on the crank shaft 16, whereby said cam shaft is driven, the arrangement being such as to provide an overhead valve mechanism in which the cam mechanism is completely inclosed and protected from dirt, dust and injury, and in which the lifter rods are properly guided to always move in a straight line, thus preventing objectionable wear and tear on the valve mechanism, while reducing the amount of noise to a material degree over valve mechanisms of that type such as occurs after the engine has been in use for some time. The chamber 44 is closed by a cover plate 52, detachably secured in position by screws or other fastenings 53, upon the removal of which access may be conveniently obtained to the valve actuating gearing for the purpose of cleaning or repairing the same or replacing any worn parts. The gear 50 is inclosed partially within the engine body and projects partially outward through a slot 54 therein, a segmental hood or cover 55 detachably secured in position by fastenings 120

- 56 being provided to inclose the projecting portion of said gear and being readily removable to facilitate the application and removal of the gear from the cam shaft.
- 5 The cams 48 are arranged to sweep in their orbits of motion through oil containing gutters 57 communicating through oil feed openings 58 with the exterior of the crank casing 2, whereby a splash feed of oil from 70 the crank casing to the gutters is secured for keeping the cams and shoes properly lubricated. As shown, the upper end of each cylinder 22 is provided with a cavity or recess 58, and this cavity or recess permits free downward movement of the inlet and exhaust valves and provides for the formation of an explosion chamber of increased area to receive the explosive charge and permit of the free escape of the 75 exhaust gas, thus insuring high power from the impulses of the working charges and a reduction of resistance to the discharge of the spent gas on the exhaust action.
- It will be observed from the foregoing description that by removing the detachable section 8 of the crank casing 2 and disconnecting the connecting rods from the wrist pins, the crank shaft with its applied parts will be readily accessible for cleaning, 80
- 30 pairs or removal, and that the pistons and connecting rods will also be rendered freely accessible and removable for the application of new piston rings or other purposes. Furthermore, it will be apparent that upon 85
- 35 moving the detachable section 9 of the cylinder casing 3 all the cylinders will be rendered accessible for independent or conjoint removal, for the purpose of regrinding them, removing carbon, substituting a new 90
- 40 cylinder or cylinders for a defective or worn out one, or for various other purposes. By removing both detachable sections 8 and 9 it will be evident that all the working parts in the crank casing and cylinder casing will 95
- 45 be exposed for inspection, repairs or other purposes. By simply disconnecting the cylinder head 29 and the pivots of the rocker arms the entire set of valves may be removed to allow the valves and valve seats 100
- 50 to be cleaned or reground and new valves to be applied whenever required, while upon removing the cover plate 52 access may be obtained to the valve actuating mechanism to enable any work to be performed thereon.
- 55 The construction of the engine with separable sections as described, furthermore enables economy and rapidity of production to be secured, as well as rapid assemblage of the parts in setting up the engine and 105
- 60 rapid disassemblage of the parts in taking down the engine, enabling the engine to be cleaned, repairs to be made or new parts substituted for defective or worn out ones with a great economy of time and labor in 110
- 65 correcting any defects and maintaining the

engine in prime working order at all times. In the event of the freezing of the engine and bursting of a cylinder, or a cylinder being found defective, it will be evident that the damaged or defective cylinder may be 70 removed and a new cylinder inserted in its place, without the necessity of discarding all or a plural number of cylinders such as is necessary when the cylinders are formed *en bloc*. By the described construction of 75 the cylinder casing and substantially spool-shaped cylinders an efficient type of water jacket is produced whereby greater efficiency is secured in the cooling of the engine, and by the described construction of 80 the cylinders with the cavities or chambers 58 greater power is secured in utilizing to the fullest extent the explosive force of the ignited charge. Other advantages of the invention, from the standpoint of economy 85 of manufacture and maintenance, and ease of cleaning, repairs and the replacement of parts, will be evident from the foregoing description without a further and extended explanation, and it will be seen that the invention provides a simple and effective type of construction for securing these manifold advantages.

While we have shown in the present instance a four-cylinder type of engine, it is 90 to be understood that the principle of the invention may be employed in an engine having any desired number of cylinders, and while we have also disclosed the use of an overhead valve mechanism any other 95 suitable and preferred type of valve mechanism may be used.

Also while we have shown and described certain preferred structures and types of means for carrying our invention into practical effect, it is to be understood that the invention is not limited thereto except when particularly specified in the claims, as any substantial equivalents thereof may be employed within the spirit and scope of the 100 invention.

Having thus fully described our invention, we claim:

1. In an engine, an elongated cylinder casing comprising longitudinally separable parts, and substantially spool-shaped separate and independent cylinders removably clamped between the separable parts of said cylinder casing.
2. In an engine, a cylinder casing comprising relatively fixed and longitudinally separable sections forming a water jacket, said sections having mating semi-circular portions forming upper and lower cylinder receiving seats, and separate and independent substantially spool-shaped cylinders clamped in vertical alignment between said cylinder sections, said cylinders having their enlarged ends fitted in said seats.
3. In an engine, an engine body formed 130

4
to provide a crank casing and a cylinder casing, each of said casings having vertically separable and removable longitudinal sections, a crank shaft journaled in the crank 5 casing and held between the separable sections thereof, a series of cylinders disposed in vertical alinement within the cylinder casing and clamped between the separable sections thereof, pistons operating in said 10 cylinders, and connecting means between the crank shaft and pistons.

4. In an engine, an engine body formed to provide a crank casing and a cylinder casing integral therewith, each of said casings being composed of relatively separable longitudinal sections, a crank shaft journaled in the crank casing and held between the separable sections thereof, a plurality of separate and independent substantially 15 spool-shaped cylinders disposed in vertical alinement within the cylinder casing and clamped between the separable sections thereof, pistons operating in said cylinders, and connecting means between the crank 20 shaft and cylinders.

5. In an engine, an engine body formed to provide a crank casing and a cylinder casing integral therewith, each of said casings being formed of separable longitudinal sections, a crank shaft journaled in and removably held between the sections of the crank 30 casing, a plurality of separate and independent cylinders disposed in vertical alinement within and clamped between the separable sections of the cylinder casing, said cylinders and the walls of said casing being relatively formed to provide a water jacket 35 having communicating channels around the cylinders, pistons operating in the cylinders, and connecting means between the crank 40 shaft and said pistons.

6. In an engine, an engine body formed to provide a crank casing and a cylinder casing integral therewith, said casings having relatively fixed connected walls at one side and removable walls at their opposite sides, a crank shaft journaled in and held between the fixed and removable walls of the crank 45 casing, a plurality of cylinders disposed in alinement within the cylinder casing and clamped between the fixed and removable walls of said casing, pistons operating in said cylinders, and connecting means between the crank shaft and pistons.

55 7. In an engine, a body formed to provide a crank casing and a cylinder casing, the bottom wall of the crank casing and one side wall of each of said casings being integral with each other, and said casings having 60 their opposite side wall detachably connected with their fixed side walls and independently removable, a crank shaft journaled in the crank casing and held between the fixed and removable side walls thereof, a series of 65 separate and independent pistons disposed in

the cylinder casing and clamped between the fixed and removable side walls thereof, pistons operating in said cylinders, and connecting means between the crank shaft and pistons.

8. In an engine, a crank casing, a cylinder casing rising from and integral with said crank casing, said casings each being composed of relatively fixed and removable longitudinal side walls, a crank shaft journaled in the crank casing and removably held between the fixed and removable walls thereof, cylinders disposed in vertical alinement relation within the cylinder casing and removably held between the relatively fixed 75 and removable walls thereof, pistons operating in said cylinders, and connecting rods between the crank shaft and pistons.

9. In an engine, an engine body forming a crank casing and cylinder casing integral therewith, said casings being divided on vertical and horizontal lines to provide relatively fixed and removable longitudinal sections for said crank and cylinder casings, said removable sections being detachably independent of each other, a crank shaft journaled in and removably held between the fixed and removable sections of the crank casing, pistons disposed within and removably held between the fixed and detachable 90 sections of the cylinder casing, pistons operating in said cylinders, and connecting means between the pistons and the crank shaft.

10. In an engine, a body formed to provide a crank casing and a cylinder casing rising from and integral with the crank casing, each of said casings comprising relatively fixed and removable longitudinally extending side sections, a crank shaft journaled in and removably held between the fixed and removable sections of the crank casing, substantially spool-shaped cylinders disposed within and having their enlarged ends clamped in alinement between the fixed and removable sections of the cylinder casing, the walls of said cylinder casing and body portions of said cylinders providing a water jacket having longitudinal and transverse communicating passages, pistons 110 operating in said cylinders, and connecting means between the crank shaft and pistons.

11. In an engine, a body formed to provide a crank casing and a cylinder casing, each of said casings including a fixed 115 longitudinal section rising from and integral with a bottom section and a corresponding removable section, a cylinder head detachably mounted upon the cylinder casing, a crank shaft journaled in the crank 120 casing and removably held between the sections thereof, vertically disposed cylinders arranged in alinement within the cylinder casing and removably held between the sections thereof, pistons operating in said cylinder 125 casing and removably held between the sections thereof, pistons operating in said cylinder 130

inders, connecting means between the crank shaft and pistons, and inlet and exhaust valve mechanism, mounted upon the removable cylinder head.

- 5 12. In an engine, a cylinder casing including fixed and removable longitudinal side sections, substantially spool-shaped cylinders held between said sections, each having its upper enlarged end provided with an
 10 expanded cavity, a cylinder head provided with inlet and exhaust ports communicating with the expanded chambers of the cylinders and independently removable from said cylinder casing, valves controlling said
 15 ports and arranged to open downwardly into said expanded chambers, pistons operating in the cylinders, connecting means between the crank shaft and pistons, valve actuating mechanism, and connecting means between the crank shaft and valve actuating mechanism.

13. In an engine, a crank casing formed to provide an integral bottom and side wall portion and a removable wall portion, a cylinder casing formed to provide a fixed wall portion rising from the integral side and bottom wall portions of said crank casing and a removable wall portion supported on the removable wall portions of said crank
 25 casing, independently removable cylinders disposed in alinement above the crank casing, and clamped between the fixed wall portion and the removable wall portion of said cylinder casing, a crank shaft journaled
 30 in said crank casing, pistons operating in said cylinders, and connecting means between the crank shaft and said pistons.

14. In an engine, a crank casing formed to provide bottom and end walls integral with one of its side walls and with each other, and a removable side wall divided from the integral walls of the casing on horizontal and vertical lines, a cylinder casing having a fixed wall portion rising from
 40 and integral with the integral side wall of said crank casing and a removable wall portion supported on the removable wall of said crank casing, cylinders disposed in alinement above the crank casing and
 45 clamped between the fixed and removable walls of said cylinder casing, pistons operating in said cylinders, bearings clamped between the integral wall and the removable wall of said crank casing, a crank shaft mounted in said bearings, and connecting means between said crank shaft and said pistons.

15. The combination with an engine including an elongated crank casing, of a cylinder casing coextensively integral with said crank casing and having one of its walls removable therefrom, cylinders arranged within said cylinder casing, and flanges arranged at opposite ends of said cylinders
 55 and providing a water space therebetween

and between the walls of said cylinder casing.

16. The combination with an engine including a crank casing, of a cylinder casing integral with said crank casing and having one of its side walls removable therefrom, and cylinders clamped between the walls of said cylinder casing, said cylinders each being formed with a groove intermediate their ends to provide water spaces between the adjacent walls of the grooves and the opposed walls of the cylinder casing.

75 17. The combination with an engine including a crank casing, of a cylinder casing having one of its side walls integral with a corresponding wall of the crank casing, and the other of its side walls removably supported on its corresponding wall of the crank casing, and independent cylinders clamped in alining relation within said cylinder casing, said cylinders each being formed with an annular groove intermediate their ends to provide water spaces between the walls of the grooves and the opposed walls of said cylinder casing.

80 90 18. An engine having a crank casing formed with one of its side walls integral with the bottom wall and portions of the end walls thereof, the other of its side walls being divided on horizontal and vertical lines with respect to the bottom and end walls thereof, means for securing the removable wall in position on the crank casing, bearings clamped between the integral side wall and the removable side wall, and a crank shaft mounted in said bearings.

95 100 105 110 115 120 125 130 19. An engine having a crank casing formed with one of its side walls integral with the bottom wall and portions of the end walls thereof, the other of its side walls being divided on horizontal and vertical lines with respect to the bottom and end walls thereof, a cylinder casing having one of its side walls and portions of its end walls integrally formed with the integral side wall and end portions of said crank casing, the other of the side walls of said cylinder casing being supported on said removable side wall of said crank casing, independent means for securing the removable side walls of said crank casing and said cylinder casing in position, bearings clamped between the integral side wall and the removable side wall of said crank casing, a crank shaft mounted in said bearings, cylinders clamped between the integral wall and the removable wall of said cylinder casing, pistons operating in said cylinders, and means connecting said pistons to said crank shaft.

20. An engine having a crank casing formed to provide an underlying bottom wall, a side wall integral with said bottom wall, a removable side wall, and end walls each divided on horizontal and vertical lines to provide one portion thereof integral with

the integral side and bottom wall and another portion thereof integral with said removable side wall, and a crank shaft journaled between abutting faces of the end wall 5 portions.

21. An engine having a crank casing formed to provide an underlying bottom wall of a width approximating the width of the crank casing, a side wall integral with 10 said bottom wall, a removable side wall, and end walls each divided on horizontal and vertical lines to provide one portion thereof integral with the integral side and bottom wall and another portion thereof integral 15 with said removable side wall, and a crank shaft journaled between abutting faces of the end wall portions.

22. An engine having a crank casing formed to provide an underlying bottom 20 wall extending substantially the full width thereof, a side wall integral with the bottom wall, a removable side wall, and end walls each divided on horizontal and vertical lines to provide one portion thereof integral with 25 the integral side and bottom wall and another portion thereof integral with said removable wall portion, bearings clamped between abutting faces of said end wall portions, and a crank shaft journaled in said 30 bearings.

23. An engine having an elongated crank casing formed to provide an underlying bottom wall extending substantially the full width thereof, a side wall integral with the 35 bottom wall, a removable side wall, and end walls each divided on horizontal and vertical lines to provide one portion thereof integral

with the integral side and bottom wall and another portion thereof integral with said removable wall portion, bearings clamped 40 between abutting faces of said end wall portions, and a crank shaft journaled in said bearings.

24. An engine having a substantially circular crank casing formed to provide an underlying bottom wall extending substantially 45 the full width thereof, a side wall integral with the bottom wall, a removable side wall, and end walls each divided on horizontal and vertical lines to provide one 50 portion thereof integral with the integral side and bottom wall and another portion thereof integral with said removable wall portion, bearings clamped between abutting faces of said end wall portions, and a crank 55 shaft journaled in said bearings.

25. An engine having an elongated crank casing substantially circular in cross-section and formed to provide an underlying bottom wall extending substantially the full 60 width thereof, a side wall integral with the bottom wall, a removable side wall, and end walls each divided on horizontal and vertical lines to provide one portion thereof integral 65 with the integral side and bottom wall and another portion thereof integral with said removable wall portion, bearings clamped between abutting faces of said end wall portions, and a crank shaft journaled in 70 said bearings.

In testimony whereof we affix our signatures.

JAMES WHITCOMB.
GAROLD C. J. GRAY.
